UNITED STATES PATENT OFFICE

EDWARD CRAIG, OF ST. JOSEPH, MICHIGAN, ASSIGNOR TO SARANAC AUTOMATIC MACHINE CORPORATION, OF BENTON HARBOR, MICHIGAN, A CORPORATION OF DELAWARE

STAPLING MACHINE

Application filed January 23, 1928. Serial No. 248,586.

This invention relates to machinery for stapling materials together, and more specifically to machinery for making wirebound box blanks or crate blanks.

Generally stated, the object of this invention is to provide a novel and improved construction whereby the work feeding means of a machine of this kind are actuated by an intermittent ratchet feed mechanism, which mechanism is driven by a continuously operating friction drive connection, whereby the continuous driving motion of this friction connection is converted by the ratchet mechanism into an intermittent feeding motion for the work feeding means, so that the work is fed intermittently below the staplers.

It is also an object to provide certain details and features of construction and combinations tending to increase the general efficiency and the desirability of a stapling machine of this particular character.

To the foregoing and other useful ends, the invention consists in matters hereinafter set forth and claimed and shown in the accompanying drawings in which—

Fig. 1 is an end elevation of a stapling machine embodying the principles of the invention, being specifically, as shown, a machine for making wirebound box blanks or crate blanks.

Fig. 2 is a side elevation of the machine shown in Fig. 1, with the left-hand end portion of said machine omitted for convenience of illustration.

Fig. 3 is a vertical longitudinal section on line 3—3 in Fig. 1.

Fig. 4 is a detail section on line 4—4 in Fig. 3.

Fig. 5 is a detail section on line 5—5 in Fig. 2.

Fig. 6 is a plan view of a crate blank made on said machine.

Fig. 7 is an edge view or side elevation of said crate blank.

Fig. 8 is an enlarged detail view showing a portion of the ratchet wheel shown in Fig. 2 of the drawings.

Fig. 9 is a view similar to Fig. 8, illustrating a different form of the invention.

As thus illustrated, the invention comprises a main body frame 1 mounted on a suitable base 2, these upright side frames being rigidly connected together by bars 3 and 4 as shown. A main driving shaft 5 is mounted in bearings in the upper portions of said side frames, and the staplers 6 mounted on the bar 3 are actuated by the eccentric devices 7, of any suitable character, carried on the said shaft 5, which latter is rotated by a clutch pulley 8 of any suitable character, said clutch pulley being controlled by a hand lever 9 through the medium of suitable connections, whereby the machine may be started and stopped at will. The machine is provided with parallel cleat guides 10 and with parallel endless feed belts 11 mounted on sprockets 12 carried by the transverse shaft 13 which is mounted in suitable bearings on the body frame at the discharge end of the machine. It will be understood that similar shaft and sprockets are provided for said feed chains at the other end of the machine, but are not shown for convenience of illustration. Said feed belts or sprocket chains are provided with means of any suitable character for propelling the cleats 14 in the guides 10, and for spacing and propelling the strips 15 of veneer or other suitable sheet material, so that the cleats and sheet material will be held in proper relative position and carried under the staplers for the insertion of the staples 16 by which the binding wires 17 are secured to the blanks, and by which the sheet material is secured to the cleats. It will be understood that the wire for forming the staples can be fed to the staplers in any suitable or desired manner, and that the binding wires can also be fed or guided into position to be stapled to the blanks, by any suitable or desired means. The blank materials are placed by hand, or otherwise, upon the feed belts, and in the cleat guides, and the materials are carried along under the staplers, and the blanks thus made are discharged at the right hand end of the machine shown in Fig. 2 of the drawings.

It will be seen that the staples 16 are not uniformly spaced, and do not occur at reg-

ular intervals on the work, and for this purpose ratchet feed mechanism is provided comprising a ratchet wheel 18 having adjustable ratchet teeth 19 on the periphery thereof, these teeth having set screws 20 by which they can be adjusted and held in adjusted position at different points on the periphery of the wheel. Gearing 21, 22 and 23 connect the shaft 24 with the shaft 13, the 5 said ratchet wheel 18 being mounted on said shaft 24 as shown, whereby rotation of said shaft 24 will rotate the shaft 13 and thereby operate the endless feed belts 11 previously mentioned. The shaft 24 is carried by an 10 adjustable bearing support 25 mounted on the frame member 26, and this member 25 is adjustable longitudinally of the frame 26 by means of the screw 27 which has a handle 28 for the rotation thereof, this screw being held against endwise displacement by the 15 bearings 29 and 30, whereby the distance between the shafts 13 and 24 can be varied to permit the substitution of gearing of a different ratio, when it is desired to change the 20 length of feed of the feed belts. The shaft 24 is driven by a friction clutch comprising the outside friction members 31, which are keyed to this shaft, and the inside driving friction member 32 which is loose on said 25 shaft, a coil spring 33 on said shaft serving to keep the friction members of the clutch crowded tightly together, and this thrust being sustained by a thrust bearing 34 of any suitable character. The member 32 is 30 driven continuously by a sprocket belt 35 operated by a sprocket wheel 36 on the shaft 5 previously mentioned, this belt being trained or guided around the idle sprockets 37 and 38 in the manner shown in Fig. 3 of the 35 drawings. This, of course, would give the feed belts 11 a continuous motion, instead of an intermittent motion, and to insure such intermittent motion the stop dog 39 is provided, pivotally mounted at 40 on the 40 arm 41 carried on the transverse rock shaft 42, which latter has another arm 43 connected by the rod 44 with the eccentric or cam device, of any suitable character, on the shaft 5 previously mentioned. A spring 45 45 connects the rod 44 with the body frame to actuate the rod in one direction. With this construction, the dog 39 is alternately interposed in the path of the teeth 19, then withdrawn, so that the ratchet wheel and the 50 gearing and the feed belts are given an intermittent motion, notwithstanding that the sprocket chain 35 and the driving member 32 of the clutch operate continuously and without interruption. In other words, the continuous friction drive is automatically converted, by the ratchet wheel and its stop dog 39, into intermittent feeding motion on the 55 part of the endless chain or feed belts, thereby to give the work the required intermittent stoppage below the staplers necessary 60 65

for the insertion of the staples. By adjusting the teeth 19 to predetermined points on the periphery of the ratchet wheel, the spacing of the staples can be controlled, and the insertion of the staples can be rendered accurate, and the points of insertion of the staples may be made to occur at irregular intervals or at any predetermined points on the blanks, depending upon the size and shape of the materials, some blanks requiring different spacing of the staples than blanks of different character.

In Fig. 9 it will be seen that the teeth 47 are integral with the sprocket wheel, instead of being detachable and adjustable as they are in Fig. 8, and sprocket wheels of this kind having integral teeth can be used if desired. For example, a plurality of these wheels can be provided, having the teeth thereof spaced differently, and one such ratchet wheel can be substituted for another, if desired, instead of using a ratchet wheel having adjustable teeth.

Thus the ratchet wheel 18 is adapted relatively to make one complete rotation for each blank made on the machine, starting from substantially the middle of one space between two blanks and terminating at the middle of the next space between blanks. In this way the ratchet wheel 18 repeats on each blank, so to speak, so that the staples will be driven and placed in the same way on each blank. The successive staples on each blank can be uniformly or non-uniformly spaced, as may be required, by using the adjustable teeth 19, or by using a plurality of interchangeable ratchet wheels of the kind shown in Fig. 9 of the drawings. When the length of the blanks is changed, then the ratio of the gearing between the ratchet wheel 18 and the shaft 13 will be changed accordingly, in order to properly locate or place the staples on the blanks. Therefore, the blanks can be made either longer or shorter, as may be desired, by substituting different gearing between the ratchet wheel 18 and the shaft 13, in a manner that will be readily understood.

What I claim as my invention is:

1. In stapling machinery, a plurality of staplers, an overhead actuating shaft therefor, in combination with work feeding means for intermittently feeding the work under the staplers, a continuously operating friction driving connection for communicating power and motion to said feeding means, driven from the overhead stapler actuating shaft, and motion-converting mechanism between said friction driving connection and said work feeding means, said mechanism having means operative to convert the continuous motion of said driving means into intermittent motion of said feeding means.

2. A structure as specified in claim 1, said mechanism comprising a ratchet wheel hav-

ing an automatically operating stop dog for intermittently stopping the rotation of said wheel, oscillatory about an axis parallel with the axis of said wheel, said ratchet wheel being driven by said friction driving connection.

3. A structure as specified in claim 1, said mechanism comprising a ratchet wheel having the teeth thereof set at irregular intervals around the periphery thereof, and an automatically operative stop dog for said wheel, oscillatory about an axis parallel with the axis of said wheel, thereby to insert the staples at irregular intervals on the work.

4. A structure as specified in claim 1, said mechanism comprising a ratchet wheel having the teeth thereof set at irregular intervals around the periphery thereof, and an automatically operative stop dog for said wheel, oscillatory about an axis parallel with the axis of said wheel, thereby to insert the staples at irregular intervals on the work, said teeth being adjustable along the periphery of said ratchet wheel, thereby to vary the spacing of the staples, and means forming a third axis of power transmission between said first axis and said second axis.

5. A structure as specified in claim 1, said friction driving connection comprising a friction clutch on the axis of said mechanism and including an endless sprocket chain for continuously driving a member of said clutch, driven from said over-head shaft.

35 6. A structure as specified in claim 1, said mechanism including a ratchet wheel having an automatically operating stop dog, oscillatory about an axis parallel with the axis of said wheel, and said driving connection comprising a sprocket wheel and a friction clutch on the axis of said ratchet wheel.

7. A structure as specified in claim 1, said mechanism comprising gearing and being adjustable to accommodate gears of different ratios to thereby lengthen or shorten the feed stroke.

8. In stapling machinery, in combination with work feeding means for intermittently feeding the work under the staplers, operative about a plurality of axes, a feed mechanism for communicating motion to said feeding means, power transmitting means from said mechanism to said feeding means, said mechanism comprising a ratchet wheel operative about a different axis and held against axial displacement and having an automatically operating stop dog oscillatory about an axis parallel with the axis of said wheel, to intermittently stop the rotation of the ratchet wheel at predetermined intervals, thereby to space the staples in predetermined manner on the work.

9. A structure as specified in claim 8, the teeth of said ratchet wheel being adjustable

to vary the action of said dog and the spacing of the staples on the work.

10. A structure as specified in claim 8, in combination with means for communicating power to said ratchet wheel, the transmission of which power to said feeding means is intermittently interrupted by said stop dog.

11. A structure as specified in claim 8, said feeding means being adapted to feed flat box blanks, said ratchet wheel having a complete rotation for each blank.

12. A machine for making box blanks, comprising work controlling means operative about a plurality of axes and having positioning elements for the different parts of each blank, mechanism for driving fasteners into the box blanks to fasten together the parts thereof, and instrumentalities controlling the operation of the work controlling means to position fasteners in the work, operative to space the fasteners in predetermined relation, said instrumentalities comprising a ratchet wheel operative about another axis and having teeth spaced around the periphery thereof, and making a complete rotation for each blank, to be thereby operative to repeat the predetermined placing of the staples on each blank, means for rotating said wheel, and an automatic stop dog oscillatory about an axis parallel with the axis of said wheel for engaging and disengaging said teeth, to intermittently stop the rotation of said wheel.

13. In stapling machinery, in combination with work feeding means for intermittently feeding the work under the staples, a continuously operating friction driving connection for communicating power and motion to said feeding means, and motion-converting mechanism interposed between said friction driving connection and said work feeding means and having means operative to convert the continuous motion of said driving means into intermittent motion of said feeding means and comprising gearing adjustable to accommodate gears of different ratios to lengthen or shorten the feed stroke.

Specification signed this 18th day of January, 1928.
